US00D961840S

(12) **United States Design Patent** (10) **Patent No.:** **US D961,840 S**
Richmond et al. (45) **Date of Patent:** **** Aug. 23, 2022**

(54) **FILTER**

(71) Applicant: **Banana Bros, LLC**, Culver City, CA (US)

(72) Inventors: **David Richmond**, Culver City, CA (US); **Howard Richmond**, Los Angeles, CA (US); **Manuel A. Montano**, Gardena, CA (US)

(73) Assignee: **Banana Bros, LLC**, Culver City, CA (US)

(**) Term: **15 Years**

(21) Appl. No.: **29/619,024**

(22) Filed: **Sep. 26, 2017**

(51) LOC (13) Cl. **27-99**

(52) U.S. Cl.

USPC **D27/194**

(57) **CLAIM**

The ornamental design of the filter, as shown and described.

DESCRIPTION

FIG. 1 is a top isometric view showing the front and top of a filter;

FIG. 2 is a bottom isometric view showing the front and bottom of the filter;

FIG. 3 is a front elevation view, with all sides having a mirror image, of the filter;

FIG. 4 is a top plan view of the filter;

FIG. 5 is a bottom plan view of the filter;

FIG. 6 is an enlarged detailed view of the portion of the filter encircled as 12 in FIG. 2;

FIG. 7 is a bottom isometric view showing the front and bottom of an alternative embodiment of the filter;

FIG. 8 is a top isometric view showing the front and top of the alternative embodiment of the filter;

FIG. 9 is a front elevation view, with all sides having a mirror image, of the alternative embodiment of the filter;

FIG. 10 is a bottom plan view of the alternative embodiment of the filter; and,

FIG. 11 is a top plan view of the alternative embodiment of the filter.

The broken lines in the drawings represent portions of the filter that form no part of the claimed design.

1 Claim, 3 Drawing Sheets
